UNITED STATES PATENT OFFICE.

WILBER H. VAN SICKEL, OF LANGHORNE, PENNSYLVANIA, ASSIGNOR TO THOS. E. DAL-
LETT CO., OF PHILADELPHIA, PENNSYLVANIA, A CORPORATION OF NEW JERSEY.

BUSH CHISEL.

Application filed September 30, 1920. Serial No. 413,707.

To all whom it may concern:

Be it known that I, WILBER H. VAN SICKEL, a citizen of the United States, residing at Langhorne, county of Bucks, and 5 State of Pennsylvania, have invented a new and useful Improvement in Bush Chisels, of which the following is a full, clear, and exact description, reference being had to the accompanying drawings, which form a 10 part of this specification.

This invention relates to an improvement in bush chisels such as are used in connection with stone dressing machines for fac- 15 ing stones.

15 The object of my invention is to provide a device of this kind which is light in weight, strong and durable, and is so constructed that I am enabled to use cuts having plane faces, without centering or locking recesses, 20 so that the cuts used therein may be made by a blacksmith from standard shapes of tool steel, without shaping any portion thereof with the exception of the cutting faces of the cuts.

25 Fig. 1 of the drawings is a face view of one form of device made in accordance with my invention.

Fig. 2 is a side elevation.

Fig. 3 is a sectional view on the line 3—3 30 of Fig. 2.

Fig. 4 is a perspective view of the gib for retaining the cuts in position in the head.

In the drawings, the reference character 35 10 designates the head and 11 the stem, which is arranged to be inserted in the socket in the stone dressing machine. 12 and 13 are jaw members extending from the head, the inner faces of which are parallel to 40 each other and at right angles to the face of the head between the jaw members. The outer faces of the jaw members are provided with transverse undercut recesses near the lower ends thereof, and 14 are U-shaped 45 clamps, the legs 15 of which are seated in said recesses. 16 is a gib having oppositely disposed flanges 17 at opposite ends of the gib, the flanges at one side being arranged to engage the sides of the head, to retain 50 the gib in position in the head, while other flanges form retainers for the butt ends of the cuts 18. These cuts are seated within a socket formed of the under face of the gib 16, the inner sides of the jaws 12 and 13, 55 the inner faces of the U-clamps 14, and two

of the flanges 17 of the gib 16, and are locked in position by a tapered key 19 seated in a key slot, in the inner face of the jaw member 12.

The cut holder is first machined from a 60 suitable blank to the form shown in the drawings, the clamps 14 are shaped with the inner faces of the legs normal to the body of the clamp. The clamps are then heated, placed into position and the legs bent in- 65 wardly into the recesses, and when the clamps are cold they will be under tension due to the contraction of metal.

In assembling, the gib 16 is first positioned in the socket, the cuts are then inserted, and 70 secured in position by the key 19.

The gib 16 is arranged to protect the bottom of the socket against the hammer blows of the cuts, and is preferably hardened to increase its resistance against the cutting ac- 75 tion of the butt ends of the cuts. The flanges thereon provide means for retaining the gib in position in the head as well as position- ing and aligning the butt ends of the cuts. As the gib is readily removable, it can be 80 replaced when worn by merely knocking out the key 19 to release the cuts.

By the provision of clamps 14 at the ends of the jaw members, I am enabled to greatly reduce the weight of the cut holder and at 85 the same time provide a more efficient device. As the clamps are placed beyond the fastening key, the spreading action of the key is resisted by the clamps which relieves the strain at the junction between the jaw members and the head. If for any reason one or both of the clamps should become fractured, they can readily be replaced by new clamps.

By the provision of these clamps, I am 90 enabled to form the socket at a very low cost, as the side walls of the jaws including the key seat can be machined by through cuts. The clamps not only form reinforces 95 for preventing the spreading of the jaws, but also form the end walls of the socket, and as the width of these clamps is less than the depth of the jaws, I am enabled to use a flanged abutment plate or gib for the 100 cuts. This flanged gib not only provides a readily renewable protecting plate for the bottom of the socket, but also provides means for positioning the cuts, so that it is unnecessary to provide centering slots or 105 grooves in the cuts. This enables me to 110

make the cuts from standard shapes of tool steel, by merely cutting to length and shaping the cutting ends of the cuts.

It will readily be understood by those familiar with the art that various changes, such as the clamps and other details of construction, may be made without departing from the spirit and scope of my invention as defined in the appended claims.

10 Having now fully described my invention, what I claim and wish to protect by Letters Patent is:—

1. A bush chisel having jaw members for the reception of cuts, tension members 15 shrunk in position on the jaw members connecting the jaws to each other to prevent spreading of the outer ends thereof, and fixed cooperative retaining means on the jaws and the tension members arranged to readily permit 20 the positioning of the tension members when expanded by heat and fixedly secure them in position when shrunk.

2. A bush chisel having jaw members for the reception of cuts, and a tension clamp on 25 each side thereof having legs engaging both jaw members near the ends of the jaw members.

3. A bush chisel having jaw members for the reception of cuts, and a tension clamp 30 on each side thereof having legs engaging both jaw members near the ends of the jaw members, the ends of said clamps engaging converging recesses in the jaw members.

4. A bush chisel having a head, a stem 35 extending from said head, the head having jaw members with parallel inner faces, there being transverse recesses in the outer faces of the jaw members on each side thereof, a tension clamp on each side of the jaw 40 members, legs on each clamp seated in said recesses, the inner faces of the jaw members and the clamps forming a rectangular socket in the head for the reception of the cuts.

45 5. A bush chisel having a head, a stem extending from said head, the head having jaw members with parallel inner faces, there being transverse recesses in the outer faces of the jaw members on each side thereof, a

tension clamp on each side of the jaw members having legs seated in said recesses, the inner faces of the jaw members and the clamps forming a rectangular socket in the head, cuts seated in said socket, there being a key seat formed in the inner face of one of the jaw members between the clamps and the inner end of the jaw member, and a key in said seat for securing the cuts in position in the socket. 50

6. A bush chisel having a head, jaws extending from the head, a U-shaped clamp on each side connecting the outer ends of the jaws to each other, said jaws and clamps forming a cut-receiving socket, cuts in said socket, there being a key seat in one of the jaws between the ends, and a key in said seat 55 for securing the cuts in position.

7. A holder of the class described for a plurality of cuts having plane seating and locking surfaces, said device having a head and a stem extending therefrom, two jaw members extending from the head having plane seating surfaces for the cuts on the inner faces thereof, there being under cut 60 transversely extending recesses in the outer face of each jaw member and near the ends thereof, U-shaped clamps under tension 75 connecting the ends of the jaw members to each other, the legs of said clamps being seated in said recesses, there being a transverse key slot in the inner face of one of the jaw members above the plane of the clamps, there being a cut receiving socket formed 80 between the inner faces of the jaw members and the clamps, a gib in the bottom of the socket, oppositely extending flanges at opposite ends of said gib, one set of flanges engaging the sides of the head to retain the gib in position, cuts in said socket abutting 85 against the face of the gib, the other flanges on the gib being arranged to retain the cuts in position, and a key in the said key slot for locking the cuts in position.

In testimony of which invention, I have hereunto set my hand, at Philadelphia, Pa., 90 on this 27th day of September, 1920.

WILBER H. VAN SICKEL.
